UNITED STATES PATENT OFFICE.

FRANK J. MONAHAN, OF JOLIET, ILLINOIS.

OPEN-TYPE BUCKET FOR EXCAVATING-MACHINES.

1,131,071.

Specification of Letters Patent.

Patented Mar. 9, 1915.

Application filed November 5, 1913. Serial No. 799,280.

To all whom it may concern:

Be it known that I, FRANK J. MONAHAN, citizen of the United States, residing at Joliet, in the county of Will and State of Illinois, have invented certain new and useful Improvements in Open-Type Buckets for Excavating-Machines, of which the following is a specification.

My invention relates to improvements in trench digging machines, and especially to a form of a so-called open type bucket adapted to be used in connection with said machines, and has for its chief object, the provision of a bucket that will be capable of digging itself free in case of a cave-in, and that will be automatically disconnected from the conveyer chain to which it is connected if a rock bed is struck, thus eliminating the damage that would otherwise be caused to the engine driving the mechanism.

Another object of my invention is the provision of digging teeth for the bucket, that are extremely strong and that can easily be replaced in case of their being broken or dulled.

Other objects and advantages of my invention will be apparent to those skilled in the art and need not be specifically set forth herein.

In the accompanying drawing forming a part of this application, I have illustrated a preferred form of my invention in the following views:

Figure 1 is a top plan view partially in section on line 1—1 Fig. 3, a portion of the top wall of my bucket being broken away so as to disclose the various transverse partitions or walls; Fig. 2 is a front end elevation or edge view of my bucket; Fig. 3 is a side elevation of a connecting arm, and a cross-section of the bucket taken on line 3—3 of Fig. 1, and Fig. 4 is a cross-section of the bucket taken on line 4—4 of Fig. 1.

Similar reference characters refer to similar parts throughout the several views.

The reference character 5 designates generally the body portion of my bucket, the same consisting of a casting having the horizontal tapering and pointed front edge or nose 5^a, and the two sides or vertically disposed cutting edges 5^b, which rise above the main portion of the bucket. The rear edge is recessed at 5^c, so as to make a clearance for the conveyer chains (not shown) when the bucket is rounding the ends of its course. Back a short distance from the front edge

5^a, and extending downwardly, is a front vertical wall 5^d, and spaced from that is a rear wall 5^e, both of which extend longitudinally the length of the bucket and parallel to the front edge of same. Transverse walls 5^f, divide the area between said walls 5^d and 5^e, and at the two extreme ends are similar walls 5^g, at a slight angle to said walls 5^d and 5^e, for the purpose hereafter to be described.

6 represents teeth substantially rectangular in cross-section, the upper and forward edges 6^a of which are tapered and sharpened. Said teeth are inserted through inclined recesses 5ⁱ, in the body of the bucket 5, their lower ends resting upon the shoulders 5^j on the wall 5^e, as clearly shown in Fig. 4, and between the walls 5^f, and are secured in place by cotter pins 7, passing through said walls 5ⁱ, and the pins 6. At the two ends, where the walls 5^g are inclined as described, the teeth 6 are held at an angle, and protrude slightly beyond the sides of the bucket.

Spaced apart, one near each end of the bucket, as clearly shown in Fig. 1, are two circular apertures surrounded by a raised boss 5^h, respectively, on the under side of the bucket, and through which are adapted to extend lugs 8^a, of arms 8, respectively. Said arms 8 extend upwardly and are formed with bosses 8^b, which are adapted to register with the extensions 9^a, of the chain link 9, to which they are secured by the rivets 10. Cotter pins 11 pass through the rear walls 5^e, and then through the lugs 8^a, thus rigidly securing said arms 8 to said bucket 5.

The bucket just described is adapted to be used in connection with the endless chains now commonly used, only instead of the bucket doing the digging, the teeth 6 accomplish this work. Said buckets are spaced substantially two or three feet apart on said chains, and in case a very wide trench or ditch is being excavated, the end teeth 6 can be removed, and several buckets may be hooked up abreast one another on their respective chains.

In case a bed of impenetrable rock is struck during the operation of digging, the cotter pins 11 will be sheared off, thus relieving any sudden shock or strain on the engine used to drive the chain, which might result in serious damage to the entire machine if means such as the cotter pins were not provided.

Having thus described my invention, what

I claim as new and desire to secure by Letters Patent, is:—

In combination with a trench digging machine, a substantially flat bucket, the front edge of which is pointed, and its two ends raised above its main body portion or face, a front and a rear wall running longitudinally the length of said bucket, and below or under said face, a series of transverse walls dividing the space between said front and rear walls into compartments, a series of teeth sharpened at their outer ends, adapted to pass through apertures in the face of said bucket and protrude forwardly

therefrom, the lower ends of said teeth abutting against shoulders in said rear wall, cotter pins passing through said transverse walls and said teeth, and arms having lugs which pass through said bucket, and cotter pins passing through said lugs, said arms being adapted to be secured to the chain of said machine.

In testimony whereof I affix my signature in the presence of two witnesses.

FRANK J. MONAHAN.

Witnesses:

G. W. HILTABRAND,
